UNITED STATES PATENT OFFICE.

JOHN S. ROWE, OF BUFFALO, NEW YORK, ASSIGNOR TO ROWE SANITARY LAVATORY COMPANY, OF DETROIT, MICHIGAN, A CORPORATION OF ARIZONA TERRITORY.

DESIGN FOR A LAVATORY.

No. 39,910.

Specification for Design.

Patented April 6, 1909.

Application filed October 5, 1908. Serial No. 456,117. Term of Patent 7 years.

To all whom it may concern:

Be it known that I, JOHN S. ROWE, a citizen of the United States, residing at Buffalo, in the county of Erie and State of New York, have invented a new, original, and ornamental Design for Lavatories, of which the following is a specification.

The accompanying drawing forming part of this specification is a perspective view of a lavatory showing the design.

I claim:

The ornamental design for a lavatory, as shown.

JOHN S. ROWE.
